UNITED STATES PATENT OFFICE.

GEORGE GODDU, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

DUPLEX FASTENER-SETTING MACHINE.

1,291,832.

Specification of Letters Patent. Patented Jan. 21, 1919.

Application filed July 21, 1915. Serial No. 41,178.

To all whom it may concern:

Be it known that I, GEORGE GODDU, a citizen of the United States, residing at Winchester, in the county of Middlesex and State 5 of Massachusetts, have invented certain Improvements in Duplex Fastener-Setting Machines, of which the following description, in connection with the accompanying drawings, is a specification, like reference characters 10 on the drawings indicating like parts in the several figures.

This invention relates to duplex machines for simultaneously inserting fasteners, such as lacing hooks or eyelets, in the edges of 15 two pieces of work or of a folded piece of work.

Duplex machines as heretofore constructed are arranged to receive work presented with the edges in which the fasteners are to 20 be set substantially opposite to each other, and the corresponding fasteners are set in axial alinement with each other. Under these conditions one portion of the work obscures the other portion so that it is difficult 25 for the operator to ascertain whether or not the fasteners are being supplied and properly inserted in the concealed portion of the work before the work is removed from the machine. One object of the present invention is to provide a machine organized to 30 set fasteners simultaneously in two edges of work presented with one edge extending beyond the other. When so presented the fasteners inserted in both edges will be open to the view of the operator as they are inserted. 35 An important feature of the invention, accordingly, consists in a duplex machine having opposed pairs of fastener setting dies, one or more of which pairs are located out of alinement with the corresponding pair or pairs.

While the invention is herein disclosed as embodied in a machine for setting two fasteners at a time, one in each edge of the 45 work, the invention could be embodied with good advantage in a machine of the gang type in which two or more fasteners are set simultaneously in both edges of the work.

The invention is herein illustrated as embodied in a duplex hook setting machine designed to set lacing hooks in the uppers of boots and in this operation the upper is folded in a non-symmetrical manner; that is to say, with the edge of one quarter opposite

to the body portion of the other quarter. 55 That quarter of the upper which is farthest from the eyes of the operator projects beyond the edge of the other quarter and where the work is handled in an inclined position the lowermost quarter will project 60 beyond the edge of the uppermost quarter. Consequently the clenched ends of the hook barrels will be visible upon the inside of the lowermost quarter and the heads of the hooks will be visible upon the outside of the 65 uppermost quarter as soon as the work has been fed past the setting instrumentalities.

Another feature of the invention consists in feeding means arranged to engage and feed the two sides of a non-symmetrically 70 folded upper or the like in an intermittent manner. As herein shown the feeding members are pivotally mounted and the shorter member has imparted to it the greater angular movement in order that the linear 75 feeding movement of both sides shall be equal.

The features above discussed and others incident to the invention will be best understood and appreciated from the following 80 description of a preferred embodiment thereof selected for purposes of illustration and shown in the accompanying drawings, in which—

Figure 1 is a view in side elevation showing the operating parts of the machine; 85

Fig. 2 is a view in perspective of the setting instrumentalities and their associated parts;

Fig. 3 is a plan view partly in section 90 showing the position of a shoe upper in the machine, and

Fig. 4 is a sectional view of the upsetting die holders and associated parts.

In one of its aspects the invention consists 95 in improvements in the machine disclosed in Letters Patent of the United States No. 1,217,088, granted February 20, 1917, on my prior application, and in the accompanying drawings only so much of that machine is 100 illustrated as is necessary for a complete understanding of the present invention.

The machine frame 2 is provided with journals for a cam shaft 4 upon which are mounted a series of cams properly timed for 105 operating the movable parts of the machine. The machine is so organized as to operate upon work presented to it in an oblique po-

sition, this being the most convenient arrangement for the operator.

In presenting the work to the machine the upper is folded and its sides placed upon the 5 opposite surfaces of a stationary guide plate 8 set in the machine frame and beveled at its outer edge to facilitate presentation of the work. In order to hold the work in position upon the guide plate 8 before the machine 10 is started and between the feeding steps a pair of clamps or presser feet 10 and 12 are provided. The upper presser foot 10 is pivotally mounted upon a spindle 22 and the lower presser foot 12 is similarly mounted 15 upon a spindle 24 and provided with a rearwardly extending arm 14 which carries a cam roller 16 arranged to run upon the cam 6 on the cam shaft 4. The presser feet are provided with interlocking arms 13 by which 20 the movement imparted to the lower presser foot 12 by the cam 6 is imparted in an equal and opposite sense to the upper presser foot 10. The lower presser foot 12 has a downwardly extending arm 18 which stands in 25 the path of a treadle actuated bell crank lever 20, by the operation of which the presser feet may be moved away from the guide plate 8 to permit the insertion of the two sides of an upper.

30 Two feed frames 26 and 28 are pivotally mounted upon an obliquely disposed spindle 30 set in a portion of the machine frame. The feed frame 26 has a forwardly extending arm in which is slidably mounted a hook 35 setting die or plunger 46 shaped at its lower end to fit the head of a hook. A plate 32 is secured to the lower side of the arm of the frame 26 in which the plunger 46 is mounted and in this plate is located an upper 40 setting die 42.

The feed frame 28 has an outwardly extending arm in which is mounted the lower hook setting die or plunger 48. Secured to the arm of the frame 28 in which is mounted 45 the plunger 48 is a die plate 34 which is shorter than the die plate 32 above mentioned and arranged to be moved in a slot or recess cut in the lower surface of the plate 32. An upsetting die 44 is mounted on the lower side of the plate 34. The arm of the frame 26 in which is mounted the upper plunger 46 is longer than the corresponding 50 arm of the frame 28 so that the two oppositely disposed hook setting dies or plungers 46 and 48 are maintained out of line with each other and are movable in parallel but offset paths.

The plungers are operated by hammers 50 and 52 pivotally mounted upon the spindles 60 22 and 24 which also carry the presser feet. The outer end of each plunger is provided with a flange which fits into an elongated piece 51 or 53 adjustably mounted upon the end of the hammer. Each piece 51 and 53 65 is provided with a flange for acting upon the

head of the plunger in the setting operation and with an overhanging shoulder which serves to retract the plunger by engaging its flange at the conclusion of this operation. The hammers have arms 51 provided with 70 intermeshing teeth and the lower hammer 52 has also a rearwardly extending arm 54 carrying a cam roller by which the hammers are operated from a cam on the shaft 4.

A pair of anvils 36 and 38 are provided 75 for holding the hooks during the setting operation. Each anvil has a flange or lip shaped to enter the opening of the hook and an outwardly extending shank 37 and 39 encircled by a spring tending normally to hold 80 the anvil outwardly away from the upsetting dies. The anvils are mounted to slide freely in the outer ends of a pair of stationary arms 76 and 78 which extend outwardly from the machine frame adjacent respectively to the 85 plunger carrying arms of the feed frames 26 and 28. In the setting operation the anvils are forced inwardly with the hooks by the action of the plungers 46 and 48, as suggested in Fig. 4. As soon as the clenched 90 hooks are disengaged from the anvils the latter are immediately moved outwardly and restored to their initial positions by the springs which encircle their shanks.

A hopper 56 is mounted in the machine 95 frame and provided with a pair of raceways 58 and 60 by which hooks are supplied to the hook holding flanges of the anvils 38 and 36, the flanges of which are normally maintained opposite the raceway ends. Hook 100 transferring means may be provided if necessary or the hooks may be supplied by gravity. Such transferring mechanism, if employed, may be similar to that shown in my co-pending application above identified 105 and is omitted from the present drawings to avoid confusion.

The setting operation is effected by the simultaneous inward movement of the two hooks by their setting plungers 46 and 48 110 under the actuation of the hammers 50 and 52. This takes place after a hook has been supplied to the flange of each anvil 36 and 38, it being understood that the barrels of the hooks are disposed in opposite directions 115 and in alignment with the respective upsetting dies 42 and 44.

At the conclusion of the setting operation the work is fed by the lateral movement of the frames 26 and 28 about the axis of the 120 spindle 30. In this operation the hammers 50 and 52 remain in their inner positions thus holding the plungers 46 and 48 in contact with the heads of the clenched hooks and the hooks against the upsetting dies. 125 The elongated flanges of the pieces 51 and 53, as shown in Fig. 2, permit the feeding movement of the plungers to take place without disengagement from the hammers.

The feed frame 26 is provided with a 130

lower arm 27 to which is pivoted a link 62 connected at its outer end to a feed link 64 and a spacing lever 66. The link 64 in turn is connected to the lower end of an oscillatory cam lever 68 operated by a cam on the cam shaft 4. The frame 28 is provided with a lower arm 29 disposed beneath the arm 27 above referred to and pivotally connected to a link 70. The link 70 is slightly longer than the link 62 and connected to the arm 29 at a point nearer the axis of the spindle 30 than the point at which the link 62 is connected to the arm 27 of the frame 26. The link 70 is also connected to the feed link 64 and the spacing lever 66 so that its outer end is moved equally and simultaneously with the outer end of the link 62. The angular motion imparted through the link 70 to the feed frame 28 is slightly greater than the angular motion imparted to the feed frame 26 but, on account of the fact that the setting instrumentalities of the frame 28 are located nearer to their axis of movement than the setting instrumentalities of the frame 26, the actual linear movement imparted to the two pairs of setting devices is equalized and both sides of the upper are fed the same distance in each feeding step.

From the foregoing description it will be apparent that each of the feed frames is pivoted for independent movement about the spindle 30 and that the shorter frame is moved the greater angular amount. By swinging the spacing lever 66 the extent of the feed may be regulated without varying the ratio of the angular movements of the two feed frames.

In using the machine herein disclosed for setting lacing hooks in the uppers of boots, the upper is first folded so that its lower quarter projects beyond the edge of the uppermost quarter, as indicated in Fig. 3. The presser feet 10 and 12 are then opened and the edges of the upper inserted upon opposite sides of the work plate 8. The position of the edge of one quarter is determined by the edge gage 72 and of the other by the edge gage 74. The presser feet are then released and allowed to clamp the sides of the upper in place and the machine is set in operation. The setting plungers 46 and 48 are immediately advanced and the hooks, which have previously been supplied to the anvil, are forced through the sides of the upper and have their ends clenched by the upsetting dies 42 and 44. The feeding operation is then effected by the lateral movement of the two feed frames and during this time the clenched hooks are carried off of the anvils. The presser feet, which are retracted automatically during the feeding operation, are operated to engage the work again at the conclusion of the feeding operation. The hammers 50 and

52 are then moved outwardly carrying the setting plungers with them, thereby releasing the work. Finally the feed frames are returned to their initial positions in readiness to repeat the cycle.

Having thus described my invention, I claim as new and desire to secure by Letters Patent of the United States:

1. A machine for setting fasteners in shoe uppers, having, in combination, work feeding means including two opposed sets of fastener setting devices constructed and arranged to insert fasteners in different directions, one set being located out of line with the other, and mechanism for feeding fasteners to each set of fastener setting devices.

2. A machine for setting fasteners in shoe uppers, having, in combination, two opposed sets of fastener setting devices constructed and arranged to insert fasteners in different directions, one set being located in the rear of the other in a direction perpendicular to the edges of the upper, and mechanism for feeding fasteners to each set of fastener setting devices.

3. A machine for setting fasteners in shoe uppers, having, in combination, two opposed sets of fastener setting devices, one set being located out of line with and below the other, and mechanism for feeding fasteners to each set of the fastener setting devices.

4. A machine for setting tubular fasteners having barrels in shoe uppers, having, in combination, two oppositely directed upsetting dies constructed and arranged to be located between the sides of an upper non-symmetrically folded and being relatively offset in a plane substantially perpendicular to the edges of the sides of the upper, and means for presenting the barrels of oppositely disposed fasteners to said upsetting dies.

5. A machine for setting fasteners in shoe uppers, having, in combination, two oppositely directed upsetting dies relatively offset in a plane substantially perpendicular to the laced edges of the upper to be operated upon, and coöperating fastener carrying dies whereby fasteners may be set at substantially equal distances within the respective edges of an upper non-symmetrically folded.

6. A machine of the class described comprising mechanism for simultaneously setting hooks in both edges of a non-symmetrically folded upper including a pair of oppositely directed upsetting dies relatively offset, and a pair of oppositely directed and relatively offset hook-carrying dies for presenting the corresponding hooks to the opposite sides of the upper.

7. A machine of the class described comprising mechanism for simultaneously set-

- ting hooks in both edges of a non-symmetrically folded upper including an intermediate die holder having upsetting dies which are directed in opposite directions and are 5 relatively offset in a direction perpendicular to the edge of the upper, and a hook-carrying die movable in a path in line with each upsetting die toward or from said die.
8. A machine of the class described comprising mechanism for simultaneously setting fasteners in both edges of a non-symmetrically folded upper including two opposed pairs of setting dies, one pair being located out of line with the other in a direction perpendicular to the edge of the upper, and mechanism for supplying fasteners to 10 each pair of dies.
9. A machine of the class described comprising means for moving fasteners in opposite directions in parallel but offset paths to insert them in the work, means for holding a non-symmetrically folded upper with its edges equally distant from the paths of the fasteners, and means for clenching the fasteners upon the upper.
10. A machine of the class described comprising fastener carrying devices movable in opposite directions in parallel but offset paths, raceways for supplying fasteners to the carriers, means for holding a folded upper with the edge of one side opposite to the body portion of the other side, and upsetting dies for clenching the fasteners at the conclusion of the operative movements 30 of the carrying devices.
11. A machine of the class described comprising mechanism for simultaneously setting fasteners in both edges of a non-symmetrically folded upper, including upper holding means, an upsetting die located near the edge of one side of the upper and opposite to the body portion of the other side, a second upsetting die located near the edge of the said other side of the upper and beyond the side first mentioned, and a fastener carrier corresponding to each upsetting die.
12. A machine of the class described comprising means for intermittently feeding a folded upper with the inner surface of one side upwardly disposed and the edge of the other side above and opposite to the body portion of the side first mentioned, and means for simultaneously inserting fasteners in both sides of the upper between the 50 steps of the feeding.
13. A machine of the class described comprising means for holding an upper folded in a non-symmetrical manner, including edge gages disposed out of alignment with each other, and fastener carriers movable in parallel paths relatively offset to correspond with the edge gages.
14. A machine of the class described comprising mechanism for simultaneously setting fasteners in both edges of a non-symmetrically folded upper including two opposed pairs of setting dies, one pair being located out of line with the other, and means for feeding both sides of the upper.
15. A machine for simultaneously inserting fasteners in both edges of a non-symmetrically folded upper, having feeding means movable intermittently in separate paths to advance the two sides of the upper.
16. A machine for simultaneously inserting fasteners in both edges of a non-symmetrically folded upper, having a pair of pivoted feeding frames, and operating mechanism connected to the frames at different distances from their axes.
17. A machine for simultaneously inserting fasteners in both edges of a non-symmetrically folded upper, having an oscillating cam lever, a pair of feed frames mounted for pivotal movement and each having work engaging means which are located at a different distance from their axes, and link connections between the cam lever and each frame constructed and arranged to impart equal linear movements to the work engaging means of both frames.
18. A machine for simultaneously inserting fasteners in both edges of a non-symmetrically folded upper, having an oscillating cam lever, a pair of oscillatory feed members having a common axis, one member having work engaging means located at a greater distance from the axis than the other, and link connections between the lever on the one hand and the two feeding members on the other hand, the point of connection with the member having its work engaging means nearer the axis being also nearer the axis than the point of connection with the other member.
19. A machine for setting lacing hooks in a non-symmetrically folded upper, having, in combination, oppositely disposed upsetting dies arranged in offset relation, hook anvils each having a hook holding portion shaped to enter the opening of a hook and being oppositely movable in relatively offset paths, and means for operating the anvils.
20. A machine for setting lacing hooks in a non-symmetrically folded upper, having, in combination, an edge gage, oppositely disposed upsetting dies offset with respect to each other in a direction perpendicular to the edge gage, a hook setting plunger movable toward and from each upsetting die, and an anvil plate interposed between each plunger and its associated upsetting die.
21. A duplex fastener setting machine, having, in combination, means for positioning two layers of sheet material with the edge of one layer opposite the body portion of the other layer and offset from the edge of the latter layer, and two opposed sets of setting devices, one set being located out of

line with the other by a distance substantially equal to the distance between the offset edges of the two layers.

22. A duplex fastener setting machine, having, in combination, means for guiding two layers of sheet material for edgewise movement with the edge of one layer opposite the body portion of the other layer, and means for inserting parallel but offset rows 10 of fasteners in the two layers respectively.

23. A duplex hook setting machine, having, in combination, means for positioning two layers of sheet material with the edge of one layer opposite the body portion of the other layer, and means for inserting a row 15 of hooks in each of said layers, one row being parallel to the other but offset relatively thereto in the direction of the front of the hook openings.

24. A machine of the class described, having, in combination, a projecting die plate 20 32 carrying an upsetting die on one surface and having a recess formed in the other surface thereof, a second die plate 34 extending movably into said recess and carrying an 25 upsetting die, and inserting dies coöperating with each of said upsetting dies.

25. A duplex fastener setting machine, having, in combination, independently pivoted tool carrying frames, work engaging 30 means carried by each of said frames adapted for engagement with one of two opposed layers of sheet material, and means for oscillating each of said frames to feed the work.

In testimony whereof I have signed my 35 name to this specification.

GEORGE GODDU.
